UNITED STATES PATENT OFFICE.

CLARENCE W. DAVOCK, OF DETROIT, MICHIGAN, ASSIGNOR TO DETROIT STEEL PRODUCTS COMPANY, OF DETROIT, MICHIGAN, A CORPORATION OF MICHIGAN.

CLIP FOR METALLIC WINDOW-SASH.

1,022,123.

Specification of Letters Patent.

Patented Apr. 2, 1912.

Application filed September 29, 1910. Serial No. 584,383.

To all whom it may concern:

Be it known that I, CLARENCE W. DAVOCK, a citizen of the United States of America, residing at Detroit, in the county of Wayne 5 and State of Michigan, have invented certain new and useful Improvements in Clips for Metallic Window-Sash, of which the following is a specification, reference being had therein to the accompanying drawings.

10 The invention relates to a construction of metallic window sashes and more particularly to the means employed for securing the window pane in position while the putty is still in a plastic condition.

15 With wooden window sashes it is a usual practice to secure the frames in position by triangular metallic fasteners the point of which are placed into the wood, but with metallic frames such devices are as a matter 20 of course not applicable. I therefore have devised a temporary fastener for the pane consisting essentially in a bendable point which engages an aperture in the sash bar and is bent to form retaining hooks for the 25 glass. This securing device may be made in various forms as illustrated in the drawings.

Figure 1 is a section through a metallic window sash showing one form of securing 30 clip; Fig. 2 is a similar view showing a modified construction; and Fig. 3 is another modification.

35 A is one of the metallic bars of the window sash which is provided with the flange B and B' against which the glass bears, and the intermediate flange C.

40 D are apertures extending through the flanges C adjacent to the flanges B, and E is the securing device engaging said aperture.

As shown in Fig. 1, the securing device E is a piece of wire bent into U shaped form, the central portion engaging the aperture

D. Parallel portions of this U shaped member extend between the cross bars C and the 45 window pane F and will permit of the insertion of the latter. To secure the panes from disengagement the end portions G of the U are bent over the glass and will then hold it from displacement. 50

In Fig. 2 a modified construction is shown in which the securing portion of the U is bent into a triangular form.

In Fig. 3 the securing portion is formed by a roll or spiral bend in the end of the 55 wire.

In all of the various constructions a bendable metallic element is employed which engages an aperture in the sash bar.

What I claim as my invention is:

1. The combination with a T-shaped mun- 60 tin, the glass being adapted to engage the angle between the stem and head of the T, and the stem having an aperture intermediate the head of the muntin and the plane 65 of the outer face of the glass, of a bendable metal clip passing through said aperture and having the ends thereof bent to bear upon the glass.

2. The combination with a T-shaped mun- 70 tin, the glass being adapted to engage the angle between the stem and head of the T, and the stem having an aperture intermediate the head of the muntin and the plane 75 of the outer face of the glass, of a metallic clip passing through said aperture and bent to form portions arranged between the ends of the glass and the stem of the muntin, the ends of said clip bearing upon the glass.

In testimony whereof I affix my signature 80 in presence of two witnesses.

CLARENCE W. DAVOCK.
